PROCESS OF AND APPARATUS FOR TREATING HYDROCARBON OILS

Filed Feb. 10, 1921

Patented May 8, 1923.

1,454,485

UNITED STATES PATENT OFFICE.

JOHN P. PERSCH, OF HOUSTON, TEXAS, ASSIGNOR OF ONE-FIFTH TO BRAINARD
TOLLES, OF HOHOKUS, NEW JERSEY.

PROCESS OF AND APPARATUS FOR TREATING HYDROCARBON OILS.

Application filed February 10, 1921. Serial No. 443,953.

To all whom it may concern:

Be it known that I, JOHN P. PERSCH, a citizen of the United States, residing at Houston, Harris County, Texas, have invented a certain new and useful Improvement 5 in Processes of and Apparatus for Treating Hydrocarbon Oils, of which the following is full, clear, and exact description, such as will enable others skilled in the art to which it appertains to make and use the same.

My invention relates to an improvement in process of and apparatus for the treating of hydro-carbon oils to better facilitate their pumping through pipe lines.

In the pumping of the heavier grades of petroleum or hydro-carbon oils through pipe lines, it is sometimes found that the oils are so heavy and viscous as to make their handling in said lines extremely difficult. In fact some grades of oil are so heavy that it is practically impossible at ordinary temperatures to pump them through the pipes.

The object of my invention is to provide 25 an apparatus by means of which the heavier grades of petroleum may be made more fluid and wherein their specific gravity is made lighter so that the oil may be caused to flow through the pipe lines without difficulty.

This object is carried out by agitating the oil in a cylindrical chamber connected with the pipe line and introducing into the oil in the process of agitation a strong blast of air under pressure so that there will be 35 formed an emulsion of air and oil, the Baume gravity of which will be much higher than was the original untreated oil, and the fluidity of the oil will be so increased that it will flow through the pipe. It is believed also that, if the air which is forced into the oil is heated to a suitable temperature, the same will act upon the oil to break up the hydro-carbon molecules to a certain extent and have the effect of making the oil permanently more fluid so that it will not return to its original viscous state.

The apparatus, by which I contemplate carrying into effect this process, is disclosed in the drawing wherein Fig. 1 is an assembly 50 view more or less diagrammatic in form, illustrating partly in longitudinal section my improved means of treating the oil. Fig. 2 is a transverse section on the line 2-2 of Fig. 1, and Fig. 3 is a similar transverse section on the line 3-3 of Fig. 1. Like char-

acters of reference are applied to like parts in the several views.

I contemplate taking the oil directly from the well or storage tanks and conducting the same through an entrance pipe 4, by way of an enlarged swaged coupling 5 and an elbow 6, to an agitating chamber 7. The agitating chamber comprises a section of pipe of somewhat larger diameter than that of the pipe line and connected at its forward 65 end to the elbow 6. At its farther end it is connected by means of a reducing swaged coupling 8 and a collar 9 to an outlet pipe line 10.

Within the agitating chamber 7 I mount 70 at regular intervals a plurality of agitating blades or vanes 11, these blades being mounted upon a longitudinal shaft 12 bearing, at its forward end, in an integral bearing member 13, and at its farther end in a bearing member 14. The bearing member 14 I have shown as supported in a spider comprising an outer ring 15 and connecting or supporting members 16, the outer member 15 being threaded on its exterior surface for attachment to the interior face of the agitating chamber 7. The blades or vanes 11 are set at such an angle upon the shaft that the rotation of said shaft will not only agitate the oil flowing through said chamber but will 80 act as a propeller to force the oil forwardly from said chamber into said pipe line 10.

The shaft 12 is caused to rotate by any well known means and I have shown a beveled gear 17 mounted on the forward end 90 thereof closely adjacent the bearing 13. This gear is in mesh with a similar beveled gear 18 driven by a power shaft 19 from a source of power not shown.

The air which is emulsified with the oil 95 during its agitation may be furnished by means of a pipe 20 connected with a compressor, or some means of air under pressure, not shown. This pipe I have shown as connected by means of a branching pipe 21 with 100 a furnace represented diagrammatically at 22, said furnace having a burner 23 and a stack 24. The pipe 21 is extended back and forward within the furnace to give as large an exposure of said pipe as possible to the 105 heat and finds an outlet from said furnace through the pipe 25. A hand valve 26 controls the passage of air through said coil 21 and a similar hand valve 27 controls the outlet from the furnace to the pipe 25. In order 110

that the air may be used cold if desired I connect with the pipe 20 another pipe 28 connecting the pipe 20 with the pipe 25 outside the furnace. This pipe is furnished 6 with a hand-operated valve 29 adjacent the pipe 21, as shown in the drawing.

The pipe 25 is connected through the side of the chamber 7 with a distributing ring 30 near the forward end of the said chamber. This ring comprises a hollow annular chamber provided on its forward face with perforations 31 through which the air is projected forwardly in the direction of the flowing oil.

15 In the operation of my device the oil is allowed to flow through the pipe 4 and its connections into the agitating chamber 7. The rotation of the shaft 12 causes the blades 11 to rotate rapidly and to churn 20 the oil up in said chamber and drive it forwardly into the pipe line. Air is forced through the pipe 25 into the discharging chamber 30 and is projected forwardly in the direction of the current of oil and is 25 churned up by means of blades 11 and an emulsion of air and oil thus results so that when the oil leaves the chamber 7 it is filled with tiny bubbles of air and its gravity is thereby raised so that it is more fluid than it was originally, and because of its fluidity 30 it is forced through the pipe line 10 much more easily. The emulsion of oil and air maintains this consistency for considerable periods of time before there is a tendency 35 to separate so that oil once emulsified with air has all the properties of an oil of much higher specific gravity and is thereby in condition to be pumped through the lines for a much greater distance without further treatment.

When the air is conducted through the furnace 22 and thereby heated, the action of the air upon the oil is also thought to break up the hydro-carbon molecules so as 45 to cause them to re-combine in different proportions so that the oil is thus caused to be permanently more fluid. The temperature of the air when thus heated can be regulated by means of the cold air 50 through the pipe 28 in an obvious manner. The valve 29 will be at first closed and the two valves 26 and 27 will be opened, in which situation the air will pass entirely 55 through the furnace, but if the air is above the desired temperature when this is done, the valve 29 may be partially opened so as to allow some cold air to enter and thus regulate the temperature of the air as it 60 enters the distributing ring 30. By means of this apparatus the oil may be emulsified with air, either heated or cold, and it is pos-

sible to heat the air to such a temperature that it will act upon the oil to permanently decrease the gravity thereof, but if desired the oil may be emulsified with cold air, in 65 which state it will also be enabled to flow more freely through pipe lines. It will thus be possible to handle the heavy and viscous oils in pipe lines where previously such oils could not be pumped therethrough.

Having thus described my invention, what I claim as new and desire to protect by Letters Patent is:

1. An apparatus for treating heavy oils to facilitate their passage through a pipe 75 line sufficiently long to materially impede its flow therethrough comprising a section of the pipe line, pipes connected thereto to supply gas under pressure, means to heat the supply of gas before it reaches the pipe 80 section, means to deliver the gas into the pipe line in a subdivided condition, and means to further mix the gas and oil while in the pipe line, said last mentioned means also arranged to force the mixture through 85 the pipe line.

2. An apparatus for treating heavy oils to facilitate their passage through a long substantially horizontal pipe line comprising 90 a section of the pipe line, tubes to supply gas to the section, means to heat the tubes, means to regulate the temperature of the supplied gas, and means to mix the gas and oil while in the pipe line and to force the mixture through the pipe line.

3. An apparatus for treating heavy oils to facilitate their passage through a pipe line comprising a section of the pipe line, tubes to supply gas to the section, means to heat part of the tube, valves and by-passages in the tubes whereby the temperature of the gas supplied may be regulated, means to cause the gas to enter the section in a fine spray, and means to mix the gas and oil while in the pipe line and to force the 100 mixture through the pipe line in its mixed condition.

4. An improved process for the treatment of heavy oil to facilitate its passage through a long pipe line, the same consisting in first heating air and then forcing it in finely divided portions into the oil while the same is in the pipe line, then mechanically agitating and emulsifying the heated air and oil to reduce the viscosity of the oil and forcing the emulsified oil through the pipe line while so emulsified.

In testimony whereof, I hereunto affix my signature this the 2nd day of February, A. D., 1921.

JOHN P. PERSCH
